Letters Patent No. 2453, Dated Sept. 25, 1866.

Design for a Carpet Pattern.

The Schedule referred to in this Letters Patent, and making part of the same.

To all whom it may concern:

Be it known that I, Eleanor J. Mey, of Lowell in the County of Middlesex and State of Massachusetts, have originated and designed a new Pattern for Carpets or other fabrics, of which the following is a full, clear and exact description, reference being had to the accompanying drawings making part of this Specification:

A, A, in the centre are groups of four leaves surrounded by a cross shaped frame B. C, is an irregular shaped figure and resting on leaves. D, D, are halves of an irregular shaped figure, and resting on leaves similar to Figure C.

E, E, E, E, are halves of four centres, the particular form is shown in the drawing. The rest of the design consists of small blocks and Spring Work.

The colors employed for the different portions of the design may be varied to suit the taste and wish of the manufacturer.

Claim

What I claim as my invention and desire to secure by Letters Patent is; The Design or Pattern for Carpets or other fabrics herein set forth. Witnessed
